UNITED STATES PATENT OFFICE.

DENNIS E. LAHEY, OF LOUISVILLE, KENTUCKY.

RAILWAY SWITCH.

Continuation of application Serial No. 605,045, filed December 5, 1922. This application filed August 21, 1923. Serial No. 658,490.

To all whom it may concern:

Be it known that I, DENNIS E. LAHEY, citizen of the United States, residing at Louisville, in the county of Jefferson and 5 State of Kentucky, have invented certain new and useful Improvements in Railway Switches, of which the following is a specification.

This invention relates to improvements 10 in railway switches, and the primary object of the invention is to furnish an improved switch for rendering the travel of a railway train safer during its passage through the switch, and is a continuation 15 of my application Serial No. 605,045, filed December 5, 1922,

Another object of the invention is to provide a railway switch having novel guard rails designed to house the switch 20 points when the latter are not cooperating with the stock rails, and to guide loose parts hanging from the train over the switch without damaging any part of the latter.

A further object of the invention is to 25 furnish improved ramps designed to be arranged between the guard rails and stock rails to facilitate the passage of the car wheels over the switch and to prevent loose parts being caught in the throats between 30 the guard rails and stock rails.

A still further object is to furnish specially formed braces for holding the guard rails in a relatively fixed position, while permitting the same to expand and contact.

35 Another object is to provide novel clamps for bonding the guard rails and stock rails together.

With the foregoing objects outlined and with other objects in view which will appear 40 as the description proceeds, the invention consists in the novel features hereinafter described in detail, illustrated in the accompanying drawings and more particularly pointed out in the appended claims.

45 Referring to the drawings:

Fig. 1 is a top plan view of a portion of a railway track having the improved railway switch mechanism incorporated therein.

50 Fig. 2 is a transverse vertical sectional view taken on line 2—2 of Fig. 1.

Fig. 3 is a longitudinal vertical sectional view taken on line 3—3 of Fig. 1.

Fig. 4 is a perspective view of one of the

clamps designed to secure a guard rail and stock rail together. 55

Fig. 5 is a similar view of one of the braces employed to hold the guard rail in position.

Fig. 6 is a similar view of the other brace for securing the guard rail in position. 60

Fig. 7 is a perspective view of one of the guard rails.

Fig. 8 is a similar view of one of the wedge blocks used with the clamps. 65

Fig. 9 is a view similar to Fig. 1, but showing a modification.

Fig. 10 is a perspective view of one of the guard rail cover plates used, forming part of the modification. 70

Fig. 11 is a perspective view of one of the clamps used with the modification.

Figs. 12 and 13 are perspective views of the braces forming part of the modification. 75

In the drawings, 1 and 2 designate stock rails mounted on ties 3 and cooperating with switch points 4 and 5.

Arranged between the stock rails are guard rails 6. These guard rails are the same in construction with the exception that one is formed to cooperate with the stock rail 1 while the other is shaped to cooperate with the stock rail 2, and as the structure of these guard rails is similar, a description of one will suffice for both. Each guard rail consists of a head portion 7 which extends from the point 8 to the point 9, and the inner edge portion of this head is provided with an offset shoulder 10, while the outer edge portion is curved inwardly from the point 11 to the opposite ends 8 and 9 of the head. The ends of the head 7 are supported by pedestals 12 and 13 which are preferably of angular shape in cross section as shown at 85 14, and are inclined downwardly in opposite directions. These inclines are designated 15 in Figure 3. It will be noted that loose parts hanging from a train passing in either direction over the track will ride up these inclines 15 so that they will not 90 be liable to catch on any fixed portion of the track and displace the same. Further, the curved outer edges 16 of the heads of the guard rails facilitate the passage of loose parts over the switch and function to force 95

100

105

the flanges of the car wheels into engagement with the heads of the stock rails.

The portions of the heads of the guard rails arranged near the ends 8 are supported

- 6 and prevented from moving toward one another by means of braces 17. One of these braces is shown detached in Figure 5, and it consists of a base 18 provided with apertures 19 to receive the spikes employed
10 in fastening the braces to the ties 3. A vertical web 20 rising from said base extends longitudinally thereof and has its inner edge 21 inclined downwardly and inwardly towards the longitudinal center of the track.
15 This web 20 supports a head 22 having a shoulder portion 23 that abuts against the inner edge 24, shown in Fig. 1, of the head 7 of the guard rail, so that the brace aids in preventing the head of the guard rail
20 from moving towards the longitudinal center of the track. The head 7 is secured to the head 22 by suitable fastening means 25, such as screws, bolts, or rivets.

- 25 The end portions of the heads of the guard rails, arranged adjacent the pedestals 13, are supported and held in position by braces 26. One of these braces is shown in Fig. 6 and it is identical with the brace 17 with the exception that the upper surface
30 27 of the head 28 between the shoulder 29 and edge 30, is of substantially the same width as the portion of the head of the guard rail which rests on the same, and this additional width is provided to permit
35 the edge 28 and the edge 31 of the brace to abut against the ramp 32, as best shown in Fig. 2. The head 28 of the brace 26 is also connected to the head of the guard rail by means of suitable fastenings 33.

- 40 Each of these ramps has an inclined end surface 34, which snugly engages the under surface of one of the inclined pedestals 13, as shown in Figure 3, and this inclined surface 34 extends across the space between the stock rail and the pedestal 13. Therefore, it will be seen from Figure 1 that any loose part hanging from a train passing in the left hand direction and striking said ramp, will ride up the inclined surface 34 and will thus be guided through the throat formed between the guard rail and the stock rail. The inclined surface 34 at its upper end merges into a substantially horizontal surface 35 which extends under the head of the stock rail as shown at 36 in Figure 2. The end of the ramp 32 opposite the inclined surface 34 is downwardly inclined as shown at 37 so that a train moving in the right hand direction in Figure 1 may also have hanging parts guided through the throats formed between the guard rails and stock rails. In Figure 2 it may be seen that the ramp has an upwardly extending part 38 on which the head 7 of the guard rail rests, and the outer surfaces of this exten-

sion 38 is inclined downwardly and outwardly as shown at 39, in order to force the flange of a car wheel toward the head of a stock rail.

In order to secure each of the guard rails 70 and the stock rail with which it cooperates together and prevent shifting of these two elements, I have provided U-shaped clamps 40, one of which is shown detached in Figure 4. This clamp has a head portion 41 75 on which the intermediate portion of the head 7 of the guard rail rests, and a shoulder 42 extends upwardly from this head and abuts against the inner edge of the head of the guard rail. The shoulder 10 of the 80 guard rail prevents longitudinal movement of the clamp 40 in one direction and fastening means 43 function to secure the intermediate portion of the guard rail to the head 41.

85 In order to hold the clamp in position, it is provided with a keyway 44 to receive a rib 44^a formed on a wedge shaped key 45 driven in between the outer arm 46 of the clamp and the outer surface of the guard rail.

47 designates a tie bar connecting the free ends of the switch points 4 and 5, and it may be readily seen from Figure 1 that the shifting of the tie bar transversely of the track, will cause the free end of one of the switch points to move from beneath the head 7 of one of the guard rails, while the free end of the other switch point is moved beneath the head of the other guard rail, 100 and thus housed.

105 The heads of the guard rails have outer beveled surfaces 5^a, as shown in Figure 2, and these beveled surfaces tend to guide the wheel flanges toward the stock rails and to prevent any hanging parts from catching on the plates 6.

The guard rail of my invention may be used universally at switch joints, frogs, or any other place where it might be applicable.

110 In the modified embodiment shown in Figs. 9 to 13 inclusive, the guard rail 6^a has a recess 6^b in its upper face intermediate its ends. This recess is adapted to enter a notch 40^b in the clamp 40^a, and as this clamp secures the top portion of the guard rail in position, it will be seen that the braces 17^a and 26^a need not have their heads 22^a and 28^a perforated, as in Figs. 5 and 6.

115 From the foregoing, it is believed that the construction, operation and arrangement of parts may be readily understood by those skilled in the art, and it is apparent that various changes may be made in the construction illustrated without departing from the spirit of the invention as expressed in the claims.

120 My beforementioned application, Serial No. 605,045, disclosed the subject matter shown in Figs. 1 to 8 of this application,

and I have filed this application to include the subject matter shown in Figs. 9 to 13 inclusive.

What is claimed and desired to be secured by Letters Patent is:—

- 5 1. In a railway track, the combination with stock rails and switch points, of guard rails arranged between the stock rails and having portions designed to house the free 10 ends of the switch points when the latter are not cooperating with the stock rails, braces supporting the heads of said guard rails, and clamps arranged between the braces for securing the guard rail heads to 15 the stock rails.
- 10 2. A railway switch as claimed in claim 1 in which the heads of the rails are supported at their ends by pedestals of angular shaped cross section.
- 15 3. A railway switch as claimed in claim 1, in which the ends of the heads of the guard rails are supported by pedestals having downwardly inclined outer faces.
- 20 4. A railway switch as claimed in claim 1 in which the outer edge of the head of each guard rail is curved inwardly in opposite directions from a point arranged in close proximity to the free ends of the switch points.
- 25 5. A railway switch as claimed in claim 1 in which the inner edges of the heads of the guard rails are provided with shoulders against which said clamps bear to prevent longitudinal movement of the guard rails 30 in one direction.

6. A railway switch as claimed in claim 1 in which ramps are arranged between certain of said braces and the stock rails, said last mentioned braces functioning to prevent the ramps from moving inwardly toward the longitudinal center of the track. 40

7. A railway switch as claimed in claim 1 in which ramps are arranged between certain of said braces and the stock rails, each of said ramps having oppositely downwardly extending inclined portions at its opposite ends, and an upwardly extending portion provided with a downwardly and outwardly inclined side surface. 45

8. A railway switch as claimed in claim 1 in which each of said braces includes a base adapted to be secured to a tie, a vertically extending web rising from said base, a head carried by the web, and a shoulder carried by the head and adapted to engage 55 the inner edge of one of the guard rails.

9. A railway switch as claimed in claim 1 in which each of said clamps includes a base portion provided with upwardly extending spaced arms, one of said arms having a head adapted to engage the under surface of the head of one of the guard rails, a shoulder adapted to engage the inner edge of the head of the guard rail, and the other arm of said clamp having a keyway, and a key extending through said keyway and engaging one of the stock rails. 60 65

In testimony whereof I affix my signature.

DENNIS E. LAHEY.
